UNITED STATES PATENT OFFICE.

FRANK OWENS, OF SHREWSBURY, NEW JERSEY.

KITE.

1,286,078.

Specification of Letters Patent. Patented Nov. 26, 1918.

Application filed September 20, 1918. Serial No. 254,936.

To all whom it may concern:

Be it known that I, FRANK OWENS, a citizen of the United States, and a resident of Shrewsbury, in the county of Monmouth 5 and State of New Jersey, have invented a new and Improved Kite, of which the following is a full, clear, and exact description.

The object of the invention is to provide a new and improved guide arranged to insure 10 a steady flight in light or strong winds and without danger of the kite taking headers. Another object is to hold the kite against sudden sidewise movement especially when flying the kite in a puffy wind. 15 Another object is to permit of hanging the kite straight for flying in line with the wind or sidewise for flying in line out of the wind thus permitting flying the kite say over a low building adjacent a high building or other 20 structure. Another object is to permit of conveniently knocking down parts of the kite for handy shipment thereof to prevent such parts from becoming accidentally detached from the main body and lost.

With these and other objects in view the 25 invention consists of certain novel features of construction as hereinafter shown and described and then specifically pointed out in the claims.

A practical embodiment of the invention 30 is represented in the accompanying drawing forming a part of this specification, in which similar characters of reference indicate corresponding parts in all the views.

Figure 1 is a longitudinal section of the 35 kite on the line 1—1 of Fig. 2;

Fig. 2 is a rear face view of the same;

Fig. 3 is a top edge view of the same;

Fig. 4 is a side elevation of part of one of 40 the fins in engagement with the backbone, part of the latter being shown in section; and

Fig. 5 is a front face view of part of the kite with one of the fins in knockdown or 45 folded position.

The body 10 of the kite is attached at its middle to the upper portion of a backbone 11, and the body 10 comprises spaced crossbars 12 and 13 carrying a covering 14 50 of cloth, paper or other suitable fabric material. The crossbars 12 and 13 are riveted, screwed or otherwise attached to the backbone 11 and are reinforced by braces 15 secured to the backbone 11 a distance from the 55 body 10 and extending obliquely outward and upward to connect by suitable fastening

devices with the crossbars 12 and 13, as plainly indicated in Fig. 2.

A bridle 20 has its ends 21 attached to the braces 15 near the upper ends thereof, and 60 the said bridle 20 is engaged by a slip knot 22 formed on the flying cord 23 adjustably secured by a knot 24 to the backbone 11 intermediate the lower edge of the body 10 and the point of attaching the braces 15 to 65 the backbone 11, as plainly indicated in Figs. 1 and 2. The terminal of the flying cord 23 is provided with the usual ring 125 to which the kite cord 126 is secured. On the lower portion of the backbone 11 is attached 70 a tail plane 25 disposed in the plane of the body 10 and formed of a crossbar 26 and a covering 27 of cloth, paper or other suitable material. The crossbar 26 is attached at its middle to the body 11, and the 75 covering 27 is preferably in the form of two triangles joined at their bases and coinciding with the backbone 11. The upper triangle has its apex attached to the backbone adjacent the point of connection of the 80 braces 15 to the backbone 11 while the lower triangle is attached at its apex to the backbone 11 near the lower end thereof. The height of the upper triangle of the covering 27 is considerably in excess of that of the 85 lower triangle, as will be readily understood by reference to Fig. 2.

The backbone 11 is made of wood or other suitable flexible material capable of being bent forwardly, as shown in Fig. 1. In 90 order to give the desired curvature to the backbone 11 use is made of a cord 30 having a slip knot connection 31 with the upper portion of the backbone 11 and having its lower end engaging a notch 32 in the lower 95 end of the backbone 11, the lower end of the cord 30 terminating in a knot 33 to prevent this end of the cord from leaving the notch 32. By moving the slip knot 31 farther out or farther in on the backbone 11 100 more or less curvature can be given to the backbone 11.

The kite is provided with a head fin 40 and a tail fin 41, of which the head fin 40 is attached to the backbone 11 in front of the 105 body 10 and the tail fin 41 is attached to the backbone 11 in front of the tail plane 25. The head fin 40 comprises a bar 42 of wood or other suitable material bent into an approximately bow shape and to this bar 110 is secured a covering 43 of cloth, paper or other suitable material. The ends 44 and

45 of the bar 42 engage apertures 46 and 47 (see Fig. 5) formed in the backbone 11, and the aperture 46 extends transversely through the backbone 11 to hold the end 44 approximately at a right angle to the backbone 11. The other aperture 47 is slanting to hold the end 45 at a corresponding slant, as plainly indicated in Figs. 1 and 4. The tail fin 41 is constructed similar to the head fin 40 and comprises a bar 50 and a covering 51, the lower end 52 of the bar engaging a straight aperture in the backbone 11 and the upper end 53 engaging a slanting aperture in the backbone 11. It will be noticed that by the arrangement described the opposite edges of the two fins 40 and 41 are slanting in opposite directions while their outer edges are approximately at right angles to the backbone 11. The rear or free edges of the coverings 43 and 51 are approximately parallel with the backbone 11 but are slightly spaced therefrom to allow air to pass from one side of a fin to the other side thereof at the corresponding body 10 or the tail plane 25. The ends 44 and 45 of the head fin 40 and the ends 52 and 53 of the tail fin 41 are preferably tapering to readily wedge into the corresponding apertures in the backbone 11. For shipping or storing purposes the fins 40 and 41 are disconnected from the backbone 11 by disengaging the ends 44, 45 and 52, 53 from the apertures in the backbone 11. In order to hold the fins 40 and 41, however, from being lost when detached from the backbone use is made of strings 60 and 61 attached at their ends to the ends 44, 45 and 52, 53 adjacent the coverings 43 and 51, and the said strings pass through the corresponding apertures engaged by the said ends to hold the fins attached to the kite when their ends are disconnected from the backbone, as shown in Fig. 5. By reference to Fig. 4 it will be noticed that the strings also serve to assist in wedging the ends 44, 45 and 52, 53 in place in their corresponding apertures.

It will be noticed that when the kite is flying the body 10 is capable of curving forward under pressure of the wind exerted against the body held on the bridle 20. Thus the body 10 tends to hold the wind to insure steady flying of the kite. The lower corners of the body 10 tend to bend rearward under heavy pressure of the wind owing to the angular position of the upper ends of the braces 15, and by this bending of the lower corners of the body 10 the kite can readily move sidewise in case the direction of the wind changes. By providing the kite with the body 10 the tail 25 and the fins 40 and 41, the kite is not liable to take headers especially as the upper fin 40 is intended to steady the kite while the lower fin 41 acts as a stationary rudder to guide the kite in its swaying movement. Both

fins tend to hold the kite against sudden sidewise movement in a puffy wind. By constructing the kite in the manner described it can readily fly in a light or a strong wind.

Providing a slip knot connection 22 between the bridle 20 and the flying cord 23 allows hanging the kite straight or sidewise for flying in line with the wind or out of line with the wind. By this arrangement the kite may be flown between a high and a low building with the kite set to fly away from the high building. It is understood that setting the slip knot sidewise beyond the middle of the bridle 20 pulls this side of the body 10 more forwardly into the wind thereby forcing the kite in the direction of this side.

It will be noticed that the fins 40 and 41 tend to exert sidewise pressure on the front and rear ends of the kite body to cause the kite to readily follow a change in the direction of the wind by exerting pressure alike on each end of the kite body thus preventing the kite from laying flat over.

When it is desired to ship or store the kite the fins 40 and 41 are detached from the backbone 11 to allow of folding the fins flat onto the body 10 and the tail plane respectively. By the use of the cords 60 and 61 the fins are not liable to be accidentally lost.

Having thus described my invention, I claim as new and desire to secure by Letters Patent:

1. A kite, comprising a body of an approximately rectangular shape, a backbone on the upper portion of which the said body is fastened, a tail plane attached to the lower portion of the said backbone and extending in the plane of the said body, the said tail plane being spaced from the said body, a head fin attached to the backbone in front of the said body and at a right angle thereto, and a tail fin attached to the backbone in front of the said tail plane at a right angle thereto.

2. A kite, comprising a body of an approximately rectangular shape, a backbone on the upper portion of which the said body is fastened, a tail plane attached to the lower portion of the said backbone and extending in the plane of the said body, the said tail plane being spaced from the said body, a head fin attached to the backbone in front of the said body and at a right angle thereto and a tail fin attached to the backbone in front of the said tail plane at a right angle thereto, and means bending the backbone forwardly between its ends.

3. A kite, comprising a body of an approximately rectangular shape, a backbone on the upper portion of which the said body is fastened, a tail plane attached to the lower portion of the said backbone and ex-

- tending in the plane of the said body, the said tail plane being spaced from the said body, a head fin attached to the backbone in front of the said body and at a right 5 angle thereto and a tail fin attached to the backbone in front of the said tail plane at a right angle thereto, and a flexible connection at the rear end of the backbone and attached at one end to the lower end thereof, 10 the other end of the said flexible connection having an adjustable connection with the upper portion of the backbone to give a desired forward bend to the said backbone.
4. A kite, comprising a body of an approximately rectangular shape, a backbone 15 on the upper portion of which the said body is fastened, a tail plane attached to the lower portion of the said backbone and extending in the plane of the said body, the 20 said tail plane being spaced from the said body and being in the form of two triangles having a common base and having their common medial line coinciding with the said backbone, a head fin attached to the 25 backbone in front of the said body and at a right angle thereto and a tail fin attached to the backbone in front of the said tail plane and at a right angle thereto.
5. A kite, comprising a body of an approximately rectangular shape, a backbone 30 on the upper portion of which the said body is fastened, a tail plane attached to the lower portion of the said backbone and extending in the plane of the said body, the said 35 tail plane being spaced from the said body, a head fin attached to the backbone in front of the said body and at a right angle thereto and a tail fin attached to the backbone in front of the said tail plane and at a right 40 angle thereto, each of the said fins having a flat body of a fabric material and a bow-shaped member to which the outer edge of the said fin body is attached, the ends of the 45 said bow-shaped member being pointed and the said backbone having apertures engaged by the said pointed ends of the bow-shaped member.
6. A kite, comprising a body of an approximately rectangular shape, a backbone 50 on the upper portion of which the said body is fastened, a tail plane attached to the lower portion of the said backbone and extending in the plane of the said body, the said tail plane being spaced from the said body, a 55 head fin attached to the backbone in front
- of the said body and at a right angle thereto and a tail fin attached to the backbone in front of the said tail plane and at a right angle thereto, each of the said fins having a flat body of a fabric material and a bow-shaped member to which the outer edge of the said fin body is attached, the ends of the 60 said bow-shaped member being pointed and the said backbone having apertures engaged by the said pivoted ends of the bow-shaped member, the free edge of the fin body being spaced from and approximately parallel with the backbone. 65
7. A kite, comprising a body of an approximately rectangular shape, a backbone 70 on the upper portion of which the said body is fastened, a tail plane attached to the lower portion of the said backbone and extending in the plane of the said body, the said tail plane being spaced from the said body, a 75 head fin attached to the backbone in front of the said body and at a right angle thereto, and a tail fin attached to the backbone in front of the said tail plane and at a right angle thereto, the said fins being detachably 80 mounted on the said backbone, and means connected with the said backbone and the said fins to allow of removing the fins from the backbone and to hold the fins in knock-down position on the kite. 85
8. A kite, comprising a body of an approximately rectangular shape, a backbone 90 on the upper portion of which the said body is fastened, a tail plane attached to the lower portion of the said backbone and extending in the plane of the said body, the said tail plane being spaced from the said body, a head fin attached to the backbone in front of the said body and at a right angle 95 thereto and a tail fin attached to the backbone in front of the said tail plane and at a right angle thereto, each of the said fins having a flat body of a fabric material and a bow-shaped member to which the outer edge of the said fin body is attached, the 100 ends of the said bow-shaped member being pointed and the said backbone having apertures engaged by the said pointed ends of the bow-shaped member, the outer end portion of each bow-shaped member being approximately at a right angle to the backbone and the inner end portion being inclined to the backbone. 105
